[57] CLAIM

The ornamental design for a forward facing warning light system, as shown and described.

DESCRIPTION

FIG. 1 is a perspective view of a forward facing warning light system showing our new design;

FIG. 2 is a top view thereof;

FIG. 3 is a front elevational view thereof;

FIG. 4 is a side elevational view thereof, the forward facing warning light system appearing the same when viewed from the opposite side;

FIG. 5 is a rear elevational view thereof;

FIG. 6 is a perspective view of a modified form of the forward facing warning light system depicted in FIG. 1-5, the embodiment of FIG. 6 including an optional rearwardly facing light subassembly mounted on the top of the forward facing warning light system of FIG. 1-5;

FIG. 7 is a top view of the forward facing warning light system of FIG. 6;

FIG. 8 is a front elevational view of the forward facing warning light system of FIG. 6 and 7;

FIG. 9 is a side elevational view of the forward facing warning light system of FIG. 6-8, the design appearing the same when viewed from the opposite side; and

FIG. 10 is a rear elevational view of the forward facing warning light system of FIG. 6-9.

The appearance of our new design, as seen from the bottom, forms no part of the claimed design.
